UNIFORM RESPONSE WIDE BAND
AMPLIFIER

Otto H. Schade, West Caldwell, N. J., assignor to
Radio Corporation of America, a corporation of
Delaware

Application October 26, 1939, Serial No. 301,320

1 Claim. (Cl. 179—171)

My present invention generally relates to wide band amplifiers, and more particularly to a novel method of, and means for, providing constant gain over the lower part of the frequency range of a wide band amplifier.

Self-bias networks are highly desirable for use in amplifiers having high g_m . Degenerative effects at zero frequency (D. C.) stabilize plate current and operating bias. This is particularly true in circuits of the type disclosed by me in application Serial No. 211,155, filed June 1, 1938, now Patent No. 2,243,442, May 27, 1941, wherein the self-biasing resistor is given a large value, and the grid resistor is returned to a direct current potential point which is positive with respect to ground, but is negative relative to cathode potential. If such an arrangement, however, is used for a wide band amplifier extending to low frequencies such as 60 cycles, the bypass condenser shunting the bias resistor causes phase shift effects at the low end of the frequency range; decreased again at the said low end also occurs. Large values of capacity, of the order of 250 mf., have therefore been used in television video amplifiers to extend the low frequency range; in such amplifiers the aforesaid problem was encountered.

One of the main objects of my present invention is to provide a compensation network in the output circuit of such a high gain amplifier, which network completely eliminates phase distortion or gain variation down to zero frequency.

Another important object of my invention is to provide a high gain amplifier operating in the video frequency range and employing a self-bias network utilizing a bypass condenser; the amplifier output circuit utilizing a network to prevent gain reduction at the low end of the frequency range and permitting reduction of the value of the bypass condenser capacity to a very low value.

Still other objects of this invention are to improve generally the efficiency and response characteristics of wide band, high gain amplifiers, and more especially to provide such amplifiers in a form such that they are reliable in operation and economical to manufacture and assemble.

The novel features which I believe to be characteristic of my invention are set forth in particularity in the appended claims; the invention itself, however, as to both its organization and method of operation will best be understood by reference to the following description taken in connection with the drawing in which I have indicated diagrammatically several circuit or-

ganizations whereby my invention may be carried into effect.

In the drawing—

Fig. 1 shows an amplifier stage embodying the invention.

Fig. 2 illustrates two stages of a video amplifier embodying the invention.

Referring now to the accompanying drawing, wherein like reference characters in the two figures designate similar circuit elements, there is shown in Fig. 1 an amplifier tube 1 which may be a high gain pentode tube of the 1851 type. The tube is provided with a cathode 2, a signal grid 3, screen grid 4, a suppressor grid 5 and a plate 6 all in the order named. The cathode 2 is connected to ground through a bias resistor 7 of large value, the resistor being shunted by the bypass condenser 8. A current source (D. C.) 9 has its negative terminal at ground potential, while its positive terminal is connected to the plate 6 through a path including the load resistor 10 and compensation resistor 11 arranged in series. The condenser 12 shunts resistor 11. The screen grid 4 is connected to an intermediate point on source 9 to establish the screen at a proper positive potential. The signal grid 3 is connected, through the grid leak resistor 13 and lead 14, to a point on source 9 which is positive relative to ground. The positive potential applied to grid 3 reduces the excessively large negative bias developed across resistor 7 to the desired negative bias value. As previously explained in my aforesaid patent application, the use of the type of biasing arrangement disclosed herein stabilizes plate current and operating bias, and is of especial advantage in circuits using high g_m tubes.

For example, where the amplifier is used to amplify video frequencies, say in a range up to 9 megacycles (mc.), the video voltage will be applied between the input terminals marked "Input," and the amplified voltage will be taken from across the series resistors 10—11. Smaller values of condenser 8 cause phase shift and decreased gain at low video frequencies; hence, large values of capacity (of the order of 250 mf.) are employed at 8 to extend the low end of the frequency range. The inclusion of compensation network 11—12 in series with load resistor 10 eliminates the aforesaid phase distortion and gain reduction, and moreover permits reduction of the value of condenser 8 to a moderate value, such as 1 mf. or less.

Without compensation the gain is substantially reduced at the low frequency end of the range,

because the input voltage must overcome the phase-opposed cathode voltage developed across resistor 7, and the cathode voltage is proportional to the cathode transconductance $g_{m(k)}$ and the magnitude R_1 of resistor 7. The network 11-12 inserted in the plate circuit does not affect the gain at the high frequency end of the range, but zero frequency gain G_0 increases to the value:

$$G_0 = \frac{g_{m(p)}(R_1 + R_2)}{1 + g_{m(k)}R_1} \quad (1)$$

where $g_{m(p)}$ is the plate transconductance of amplifier tube 1; R_1 is the value of resistor 10; R_2 is the value of resistor 11.

The value of R_2 necessary for a zero frequency gain equal to the high frequency gain is obtained from the following expression:

$$R_2 = \frac{I_k}{I_b} g_{m(p)} R_1 R_1 \quad (2)$$

where I_k is the cathode current; I_b is the plate current.

In order to obtain further constant gain at other frequencies the condenser 12 must produce the same phase shift of voltage across resistor 11 against voltage across resistor 10, as the phase shift caused by condenser 8 of voltage across bias resistor 7 with respect to the grid to cathode voltage of tube 1. This is the case when the time constants are equal:

$$C_1 R_1 = C_2 R_2, \text{ or } C_2 = \frac{R_1}{R_2} C_1 \quad (3)$$

where C_1 is the capacity magnitude of condenser 8, and C_2 is the capacity value of condenser 12. The correction network 11-12 is fully determined by Equations 2 and 3. The minimum value of capacities C_1 and C_2 depends on the shunt capacity C_s across the entire plate load (tube and circuit capacities). C_2 should be a short-circuit when the shunt-capacity C_s begins to affect circuit performance. For a 1% error there is obtained $C_2=100 C_s$.

By way of specific illustration, and in no way restrictive or limiting, the following constants are given for an amplifier embodying the invention:

$g_{m(p)}=10,000$ micro-mhos
 $g_{m(k)}=13,000$ micro-mhos
 $I_b=10$ milli-amperes (ma.)
 $I_k=13$ milli-amperes (ma.)
 $E_p(\min.)=100$ volts (v.)
 $E_b=300$ volts
 Resistor 10=R₁=3000 ohms
 $C_s=20$ micro-micro-farads (mmf.)
 $E_{cl}(\text{signal grid bias})=-1$ volts
 Resistor 11=R₂=17,000 ohms
 Resistor 7=R₁=436 ohms
 Condenser 12=C₂=0.002 micro-farads (mf.)
 Condenser 8=C₁=0.078 micro-farads (mf.)

A practical choice of values for the biasing and compensation networks comprises assigning values of 0.1 mf. for C_1 and 400 ohms for R_1 , while C_2 is made equal to 0.00256 mf., and R_2 is given a magnitude of 15,600 ohms.

In Fig. 2 there is shown the amplifier circuit of Fig. 1 embodied in a multi-stage video amplifier. The amplifier, in actual operation, had a flat frequency response from 20 cycles to 9 mc. Here, as in Fig. 1, amplifier tube 1 is of the 1851 type, and includes biasing network 7-8 in its grounded cathode lead. The signal grid 3 is connected to a coupling condenser 15 which acts to transmit video voltage to the grid; the grid leak resistor 13

returns to ground through resistor 16, and condenser 17 bypasses the junction of resistors 13 and 16 to ground. Screen grid 4 is connected to the positive terminal of the 300 volts current source 9 through resistor 18, and bypass condenser 19 grounds the grid end of the resistor.

The junction of resistors 13 and 16 is connected to the positive terminal of current source 9 through resistor 20. The suppressor grid 5 is connected to the positive terminal of current source 9 through a resistor 21, while the grid end of resistor 21 is connected to ground through a resistor 22. The plate 6 of the amplifier tube is connected to the positive terminal of current source 9 through a path which includes coil 30, coil 31, resistor 10, resistor 11 and resistor 32 all arranged in series. The junction of resistors 11 and 32 is connected to ground through the condenser 33, while the condenser 12 is connected to ground from the junction of resistors 10 and 11. The succeeding amplifier 50 is coupled to the junction of coils 30 and 31 through the condenser 49; the desired negative bias is provided for the signal grid of amplifier tube 50 through a path which includes resistor 51. The plate shunt capacity C_p is shown in dotted lines as connecting the plate end of coil 30 to ground, whereas the reference character C_{g2} denotes the dotted line capacity connected between the junction of coils 30 and 31 to ground.

The network 11-12 of Fig. 2 acts as the compensation network which corrects for the phase shift and reduced gain at the low frequency end of the video range caused by biasing network 7-8. The compensation network 11-12 will not affect the performance of additional networks to extend the high frequency end of the range, nor will it prevent operation of compensation circuits for correcting voltage losses and phase shifting due to the coupling condenser 40 and the leak resistor 51. In other words, there is shown in Fig. 2 in the plate circuit of amplifier tube 1 various other compensation networks such as 32-33 and 30-31 which act to compensate for other voltage losses at low frequencies and at the high frequency end of the video range. The following table of constants is given by way of illustration for the various elements utilized in Fig. 2:

50	$C_{15}=0.05$ mf.
	$C_{17}=0.004$ mf.
	$C_8=0.1$ mf.
	$C_{19}=1$ mf.
	$C_p \approx 7$ mmf.
55	$C_{g2} \approx 14$ mmf.
	$C_{12}=0.004$ mf.
	$C_{33}=8$ mf.
	$C_{40}=0.05$ mf.
	$R_{13}=0.5$ megohms
60	$R_{16}=10,000$ ohms (variable between 5000 and 15,000 ohms)
	$R_{20}=7,000,000$ ohms
	$R_7=400$ ohms
	$R_{18}=75,000$ ohms
65	$R_{21}=200,000$ ohms
	$R_{22}=10,000$ ohms
	$R_{32}=3,000$ ohms
	$R_{11}=10,000$ ohms
	$R_{10}=2,000$ ohms
70	$R_{51}=0.5$ megohms
	$L_{30}=60$ microhenries
	$L_{31}=30$ microhenries

The resistor 16 in Fig. 2 is adjustable in order to vary the signal grid bias, which in turn varies the values $g_{m(p)}$ and $g_{m(k)}$ of pentode 1. This

variation effects Equations 1 and 2 permitting therefore, adjustment for perfect compensation in case the values R_L , R_1 or R_2 are somewhat in error as may be the case in practical circuits.

Resistors 20 and 16 provide a potential divider to obtain a small positive bias from source 9 to counteract the excess negative voltage produced across element 7. Resistors 21 and 22 provide, also, a potential divider to obtain a small positive suppressor grid bias from source 9. The latter small bias causes the "knee" of the plate current-plate voltage curves to occur at a lower plate voltage thereby permitting higher resistance values with consequently lower plate voltage in the plate circuit without loss of g_m . The voltage drop across resistor 7 in Fig. 2 is in bucking relation to the voltage drop across bleeder 16. Assuming a drop of +5.2 v. across resistor 7 and a drop of +4.2 v. across bleeder 16, then the effective bias of grid 3 will be -1 v. Actually these values are not critical because of the degenerative action which causes the cathode current to readjust itself. The network 32-33 compensates for phase shift and voltage drop at low frequencies caused by coupling condenser 40 and resistor 51. Coils 31 and 30 together with tube capacitances C_p and C_{g2} provide a low pass filter section, and this network is operative at high frequencies only and extends the frequency range, but does not interfere with the low frequency compensation. In the absence of network 11-12 the frequency response would drop at about 100,000 cycles to approximately 16% response at 1000 cycles.

While I have indicated and described several systems for carrying my invention into effect, it will be apparent to one skilled in the art that my invention is by no means limited to the particular organization shown and described, but that

many modifications may be made without departing from the scope of my invention, as set forth in the appended claim.

What I claim is:

- 5 In a video amplifier network capable of amplifying frequencies in a range up to approximately 9 megacycles, an electron discharge tube provided with at least a cathode, a signal grid and an output electrode, a source of video voltage
- 10 coupled between the signal grid and cathode, a self-biasing network comprising a resistor of relatively high magnitude of the order of 400 ohms located between said cathode and at a point of relatively fixed potential, means for applying the direct current voltage developed across said resistor to said signal grid, means for applying a direct current potential of positive polarity to said signal grid in opposition to said bias resistor voltage thereby to reduce the voltage applied to the signal grid to a normally low negative bias value, a capacity of the order of 1.0 microfarad shunted across said bias resistor, a pair of inductances and a load resistor serially connected between the output electrode and
- 15 cathode of said tube, a correction network consisting of a resistor arranged in series with said load resistor, a condenser shunting said correction resistor, said correction network having its constants chosen to compensate for a decrease in response at the low frequency end of the video range, said correction network and biasing network having substantially equal time constant values, and a second amplifier tube having its input electrode coupled to the common terminal
- 20 between said pair of inductances included in the output circuit of the first tube.
- 25
- 30
- 35

OTTO H. SCHADE.
